UNITED STATES PATENT OFFICE.

DUNCAN W. PATTERSON, OF PHILADELPHIA, PENNSYLVANIA, ASSIGNOR TO FOAMITE FIREFOAM COMPANY, OF NEW YORK, N. Y., A CORPORATION OF DELAWARE.

FIRE-EXTINGUISHER.

1,306,617.

Specification of Letters Patent. Patented June 10, 1919.

Application filed May 16, 1916, Serial No. 97,814. Renewed April 29, 1919. Serial No. 293,558.

To all whom it may concern:

Be it known that I, DUNCAN W. PATTERSON, of Philadelphia, in the county of Philadelphia and State of Pennsylvania, have invented certain new and useful Improvements in Fire-Extinguishers; and I do hereby declare the following to be a full, clear, and exact description of the invention, such as will enable others skilled in the art to 10 which it appertains to make and use the same.

This invention relates to fire extinguishers using liquid fire extinguishing chemicals.

In the use of hand extinguishers employing two or more chemicals which when the device is to be used are combined to form a carbonic acid gas foam for extinguishing purposes the entire quantities of chemicals used to form such foam must be employed. 15 This frequently causes unnecessary waste and requires the replenishing of the extinguisher after every use. It is one of the objects of my invention to provide a simple and efficient fire extinguisher wherein the chemicals which are to be combined may be separately stored until needed, and to render unnecessary the refilling of the extinguisher after each use, improved means being employed to regulate the use of only so much 20 of the chemical compounds as may be required, the remaining portions being left undisturbed and ready for further use. A further object of the invention is to provide improved means for readily combining and 25 mixing the fluids to create the required extinguishing foam.

In the accompanying drawings, Figure 1 is a vertical sectional view of my extinguisher. Fig. 2 is a detail perspective. Fig. 40 3 is a cross sectional view on line 3-3, Fig. 1.

Referring to the drawings, the extinguisher is shown in the form of a container comprising two semi-cylindrical tanks, 1 and 45 2. These tanks are designed to be secured together to form a unitary structure, their flat faces being brazed or soldered to each other. Each of such faces is provided with a recess 3, which is co-extensive with the 50 length of the container, such recesses form-

ing a mixing chamber 4. The upper and lower ends of the tanks and the mixing chamber are closed by heads 5 and 6, respectively, the lower head 6 being provided with a centrally disposed opening 7 into which a 55 discharge nozzle 8 is designed to be fitted.

Depending from the head 5 and extending into the tanks 1 and 2, respectively, are tubes or pipes 9 and 10. These tubes extend to within a short distance of the bottom of the 60 containers. Similar tubes or pipes 12 and 13 are fitted in the head 5, and extend well down into the mixing chamber 4. These several tubes are the media through which the solutions in the two tanks are introduced 65 into the mixing chamber where such solutions combine to form the extinguishing gas.

Arranged centrally of the head 5, and with its upper end secured thereto, is an air pump cylinder 14, such cylinder occupying the upper portion of the mixing chamber and being provided with the usual piston 15 and piston rod 16, the latter being connected to an operating handle 17. Air for the pump is supplied through a bore 18 in the handle. 70

The lower end of the pump cylinder forms a support for one end of a discharge pipe 20, the other end of the pipe being secured to the discharge nozzle, thus holding the apparatus together. At its upper end the discharge pipe 20 is provided with a series of 75 openings 21 through which the extinguishing foam escapes to the discharge nozzle.

Superimposed on the head 5 is a rotatable valve disk 23 by means of which communication is established between the solution tanks and the mixing chamber as well as between the air pump and the solution tanks. The valve is provided with ports 25, 26, the former constituting the passageway between the 80 tube 9 of the solution tank 1 and the tube 12 of the mixing chamber, while the port 26 forms a like communication between the tube 10 of solution tank 2 and the tube 13 of the mixing chamber. A second series of ports 85 28 and 29 establishes an air passage from the pump cylinder to the respective solution tanks through openings 30 and 31, respectively, in the head 5. The ports 28, 29 are provided with one way spring valves 32 90

100

which prevent the escape of the compressed air when the pump piston is partaking of its return stroke.

The disk valve is held to the head 5 by means of a clamping ring 33 such ring also forming a lock to prevent operation of the device except when the pump handle is turned so as to register with cut-outs 34 in the ring. The base of the handle is seated in a recess 35 in the valve, such connection between the handle and valve being the means by which the latter is turned on the head 5. The valve is provided with stops 36 to regulate its turning movement.

15. In the use of my fire extinguisher I prefer to employ two solutions, one an acid solution which is preferably of aluminum sulfate, such solution being confined in one tank, and the other a solution of bicarbonate of soda, 20 to which is added a foam making substance, which latter may be glue, glucose, soap bark, wood extract, or any substance which will make foam and retain the carbonic acid gas liberated by the reaction between the acid 25 and alkaline solutions. The solution of the bicarbonate of soda with its foam making content is confined in the second solution tank 2.

When it is desired to mix these two solutions so as to form a fire extinguishing compound the valve 23 is turned by the handle 17 so that the ports of the valve will establish communication between the respective tubes of the solution tanks and the mixing chamber as well as between the openings in the solution chambers and the air pump. The handle being then in line with the cut-outs 34, the pump piston is reciprocated forcing air into the solution tanks to 30 displace the solutions which find egress through the respective tubes 9 and 10 into the mixing chamber by way of the tubes 12 and 13. As the respective solutions are admixed, a foam is produced within the mixing chamber consisting of millions of minute bubbles of pin-head size, these bubbles containing the carbonic acid gas. Such foam is discharged through the tube 20 and the discharge nozzle 8. It is readily apparent that after a sufficient quantity of foam has been formed, the valve 23 may be quickly turned to close the intercommunicating passageways, thus shutting off further supply of the solutions to the mixing 45 chamber. Thus it will be seen that by this means a large saving is effected, it being unnecessary to empty the tank upon every use of the extinguisher. The solutions are mixed in the quantities desired, and after 50 the device has been once used it is only necessary to turn the valve leaving it in condition for further immediate or later use.

I claim as my invention:

1. In a device of the character described, 65 a plurality of adjacent solution tanks, con-

tiguous walls of said tanks being recessed to form a mixing chamber, and said chamber having an outlet, a valve for establishing and closing communication between each solution tank and said mixing chamber, and a pump for supplying the contents of said tanks to said mixing chamber.

2. In a device of the character described, a plurality of solution tanks, a mixing chamber having an outlet, a pump, and a valve for establishing communication between each solution tank and said mixing chamber and between said pump and said solution tanks.

3. In a device of the character described, a plurality of tanks for chemical solutions, a mixing chamber to which said solutions are designed to be supplied to form a foam, said mixing chamber having an outlet, a pump for supplying said solutions to said chamber, and a valve for controlling communication between said solution tanks and said chamber and between said pump and said tanks.

4. In a device of the character described, a plurality of solution tanks having each an outlet and an air port, a pump for supplying air to said solution tanks, a mixing chamber with which said solution tanks are designed to communicate through said outlets, said mixing chamber having a discharge nozzle, and a valve for controlling the air ports and the outlets to said solution tanks.

5. In a device of the character described, a plurality of solution tanks having each an outlet and an air port, a mixing chamber having inlets and an outlet, a valve controlling communication between the outlets of said solution tanks and the inlets of said mixing tank, and a pump for supplying air to said solution tanks.

6. In a device of the character described, a plurality of solution tanks having each an outlet and an air port, a mixing chamber having inlets, a pump located in said mixing chamber, and a valve having a series of passages for establishing communication between said outlets of said solution tanks and the inlets of said mixing chamber, said valve having a second series of passages through which air is supplied to said tanks.

7. In a device of the character described, a plurality of solution tanks having each an outlet and an air port, a mixing chamber having inlets, a pump adjacent said solution tanks, a rotatable valve having a series of passages for establishing communication between said outlets of said solution tanks and the inlets of said mixing chamber and between said pump and the ports of said solution tanks, and a handle for manipulating said pump and controlling said valve.

8. In a device of the character described, a plurality of solution tanks having each

an outlet and an air port, a mixing chamber having inlets, a discharge pipe communicating with said mixing chamber, a pump adjacent said solution tanks, a rotatable 5 disk valve having a series of passages for establishing communication between said outlets of said solution tanks and the inlets of said mixing chamber and between said

pump and the ports of said solution tanks, a handle for manipulating said pump and controlling said valve, and a locking ring for regulating the movement of said handle and said valve.

In testimony whereof I have signed this specification.

DUNCAN W. PATTERSON.
